BLEACHER SEAT

Application filed October 29, 1928. Serial No. 315,738.

This invention relates to improvements in bleacher seats and it consists of the matters hereinafter described and more particularly pointed out in the appended claims.

5 The primary object of the invention is to provide bleacher seats of simple though more rigid construction and which may be produced with less labor and material cost and which seats may be readily set up for use 10 and taken down for storage.

Another object of the invention is to provide a structure of this kind, wherein no corner cutting or trimming is necessary for the front end of the stringers and the front seat 15 is brought closer to said ends though still maintained at that height insuring a comfortable sitting position for the occupants.

Still another object of the invention is to provide a structure of this kind wherein the 20 seat supporting stringers are positively held against shifting endwise in either direction under the action of the load imposed upon the structure by the occupants.

Still a further object of the invention is to 25 provide a structure wherein the provision of a floor plate for each stringer is eliminated, thus avoiding the heretofore necessary trenching or grading and leveling for such stringers.

30 These objects of the invention as well as others, together with the many advantages thereof will more fully appear as we proceed with our specification.

In the drawings:—

35 Fig. 1 is a view in end elevation of bleacher seats embodying our improved construction.

Fig. 2 is a perspective view showing the manner of mounting a stringer on a toe strip which is common to a plurality of such 40 stringers.

Fig. 3 is a longitudinal vertical section through the parts shown in Fig. 2.

Fig. 4 is a view in front elevation of the parts shown in Fig. 2.

45 Fig. 5 is a horizontal sectional view as taken on the line 5—5 of Fig. 3.

Fig. 6 is a detail view of a cable clamp employed in our improved bleacher seats and which will be more fully described later.

50 Referring now in detail to that embodiment of our invention, 1 indicates as a whole one of a plurality of the seat supporting stringers, each in the form of an edgewise disposed board of the desired length, width and thickness. All of said stringers extend 55 upwardly and rearwardly from their front ends, which though not directly engaged with, are disposed above a toe strip 2 common to all or any number of the stringers, said stringers being supported by longitudinally spaced stands or jacks 3—3 as they are known in the trade of successively increased heights from front to rear to give the desired inclination to said stringers. The stands and stringers have double hook, inter- 60 engaging, detachable parts but as they form no particular part of the present invention it is not thought necessary to show or describe them in detail.

On the toe strip 2, are secured in longitudinally spaced relation, pairs of angle bar like brackets 4—4. The individual brackets of each pair extend transversely of the toe strip and the spacing of the several pairs longitudinally of the toe strips, of course 70 determines the spacing of the seat stringers which are operatively engaged therewith as will later appear. Each bracket includes a horizontal flange 4^a which engages upon and is fixed to the top surface of the toe strip in any suitable manner, and an upright flange 4^b in which openings 4^c and 4^d are formed.

On the front end of each stringer we provide a casting indicated as a whole by the numeral 5. Each casting which is of an open frame construction is of a width to fit between the brackets 4—4 of a pair thereof and includes a horizontally disposed elongated rectangular flat base 6 and an upwardly and rearwardly inclined plate 7 connected to the base near the front end by a short curved standard 8 and near the rear end by an up- 80

right standard 9 thus leaving an opening between the several parts described, as is apparent from Fig. 3. Made integral with the front end of the inclined plate 7 and extending 85

upwardly at a right angle thereto is an apertured end wall 10 and said end wall is connected at each side to said plate by sub- 90

stantially triangular open brace walls 11 in 95

100 Referring now in detail to that embodiment of our invention, 1 indicates as a whole one of a plurality of the seat supporting stringers, each in the form of an edgewise disposed board of the desired length, width and thickness. All of said stringers extend 55 upwardly and rearwardly from their front ends, which though not directly engaged with, are disposed above a toe strip 2 common to all or any number of the stringers, said stringers being supported by longitudinally spaced stands or jacks 3—3 as they are known in the trade of successively increased heights from front to rear to give the desired inclination to said stringers. The stands and stringers have double hook, inter- 60 engaging, detachable parts but as they form no particular part of the present invention it is not thought necessary to show or describe them in detail.

which are formed registering openings 12-12. The end of each stringer 1 fits within the pocket provided by the plate 7 and walls 10 and 11 respectively and bolts 13 extend transversely through suitable openings in the end of said stringer and through said openings 12-12 to partially secure the casting to the stringer end. In the rear end of the plate 7 beyond the standard 9 is an opening 14 through which a drive screw 15 is driven edgewise into the bottom of the stringer. By means of this construction the front edge of the stringers is disposed at a right angle to the top and bottom edges so that the stringers 15 can be used as they come from the mill without any further corner cutting as heretofore necessary.

On the top edge of each stringer are longitudinally spaced brackets 16 to receive and hold the seat boards 17 while on the bottom edge of each stringer are longitudinally spaced brackets 18 to receive and hold the foot rest boards 19, the foot rest boards being disposed in planes between those of the seat boards. By the construction thus far described, it is possible to place the lower front-most seat board right close to the front end of the stringers and which board will still be disposed at a comfortable sitting height above the ground and at the same time will eliminate any stringer ends forward of the stringers for the people to stumble over in ascending the structure as a whole to the desired seat board.

35 In assembling the bleacher seats, after inserting a bolt 20 through the front holes 4^a of each pair of brackets, the toe strip 2 which is common to a plurality of stringers is laid in place and should the ground or other surface be uneven, it, of course, will have to be first levelled off. In this connection it is pointed out that with the use of a toe strip, the necessity of further levelling off for the usual foot plate heretofore associated with each stringer 40 is avoided and in this respect both a considerable material and labor cost is saved.

After the toe plate, with the bolts 20 thereon is in place, the stringers each with a casting 5 thereon are positioned with respect to the 45 associated pair of brackets 4. This is done by inserting the front end of the base 6 between the brackets of each pair from the rear of the toe strip and pushing the stringer forwardly until the short curved standard 8 engages the bolt 20 after which another bolt 21 is inserted through the rear holes 4^a of the brackets a short distance to the rear of said standard 8. This structure prevents undue shifting of the stringers with respect to the 55 toe strip when the occupants are moving about the assembled seat structure or are jumping up and down due to excitement as when observing a game of some kind.

The successive stands 3-3 are then applied 60 to the stringers to support them in place and

give them the desired upward and rearward inclination. After the seat structure has thus far been assembled, we place a clamp carrying strip 22 in position upon the ground to engage with the rear of the bottom ends of the rearmost stands, this strip carrying a plurality of cam lever like cable grips or clamps 23 so disposed as to come midway between the legs of said rearmost stand. Thereafter we provide a cable 24 having a clevis 25 at one end which is hooked around the rearmost standard 9 of the associated casting 5 and the rear end of said cable is inserted through a clamp 23 and is then drawn taut. When thus clamped or gripped said cable is under tension and thus makes the entire structure more rigid. The seat and foot boards are then placed in position and the structure as a whole is ready for occupancy. To take down the structure, the operation will, of course, be the reverse.

The structure described has many advantages: It eliminates the use of individual floor plates for each stringer and also the corner cutting on the stringers and thus considerably reduces material labor and assembly cost. It also provides a structure wherein the stringers are rigidly secured in place against shifting under the jumping up and down of the occupants during excitement which has often-times resulted in accidents due to collapse of entire structure caused by such stringer shifting. On the whole there is produced a much stronger, rigid and cheaper structure which may be more easily handled with less help in erecting the same or taking it down for storage.

While in describing the invention we have referred in detail to the form, construction and arrangement of the various parts thereof, the same is to be considered merely as illustrative and we therefore do not wish to be limited thereto except as may be pointed out in the appended claims.

We claim as our invention:

1. A bleacher seat structure embodying therein, stringers, supporting stands therefor, a member disposed beneath one end of said stringers, means providing upright spaced flanges on said member, a bracket enclosing a part of the bottom, end and sides of one corner of the stringer and including a flat base adapted to engage upon said member between said flanges and means extending through a part of said bracket and said flanges for preventing longitudinal shifting of said stringer in either direction with respect to said member.

2. A bleacher seat structure embodying therein a plurality of laterally spaced stringers, supporting stands for each stringer, a member disposed transversely of and beneath one end of a number of stringers, means providing a pair of upright spaced flanges on said member for each stringer, a

- bracket enclosing a part of the bottom, end and sides of one corner of each stringer and each including a base to engage on said member between the associated pair of upright flanges thereon, and means extending through the flanges of each pair and a part of the bracket therebetween for preventing longitudinal shifting of said stringers in either direction with respect to said member.
- 10 3. A bleacher seat structure embodying therein, a stringer, supporting stands therefor, a member disposed beneath one end of said stringer, coacting parts on said stringer and member respectively for preventing longitudinal shifting of said stringer in either direction with respect to said member, a cable connected at one end to said part on said stringer and capable of being tensioned, and means to the rear of one of said stands 15 for anchoring the other end of said cable after it has been so tensioned.
4. A bleacher seat structure embodying therein a stringer, supporting stands therefor, a member fixed to one end of the stringer and including a base and a part rising therefrom, but spaced from one end thereof, a second member disposed beneath said end of the stringer spaced upright flanges on said second member and transverse bolts connecting said flanges and engaged with a part of said member fixed to said stringer to prevent longitudinal movement of said stringer in either direction.
5. A bleacher seat structure embodying 35 therein a stringer, supporting stands therefor, a casting fixed to one end of said stringer and including a plate and a base connected together by integral front and rear portions, a member beneath said end of the 40 stringer, spaced side flanges thereon between which the base is disposed, means carried by said flanges and engaging to the front and rear of said front portion above the base to secure the casting against movement with respect to said member, a clamp carrying member arranged to the rear of one of said legs, a clamping device thereon and a tension member connected at one end to said rear portion and engaged at its other end in said 45 clamp.
6. A bleacher seat structure embodying 50 therein an edgewise disposed stringer having a front end arranged at substantially a right angle to the edges thereof, supporting stands for said stringer, a casting fixed to said front end of said stringer and including a horizontally disposed base and an upwardly and rearwardly extending plate, means connecting said base and plate, a member disposed beneath said end of said stringer, spaced flanges on said member between which said base may be disposed and devices extending between said flanges and so disposed with respect to said base and connect-
- ing means as to lock said casting against movement with respect to said flanges.
7. In a bleacher seat structure, a casting comprising a horizontally disposed base and a plate above the same but inclined upwardly with respect thereto, front and rear parts connecting said base and plate, a wall rising from one end of said plate and disposed at a right angle thereto and apertured parts disposed at the sides of said plate and connecting the side portions of said wall thereto.
8. In a bleacher seat structure, a stringer, a member associated with the stringer and including a base and part rising therefrom to receive and be secured to a corner part of the stringer, a second member disposed beneath the base and upon which said base engages flanges rising from said second member, one on each side the base and devices removably secured to the flanges and so engaging the base and said part rising therefrom, as to hold said base down upon said second member and against longitudinal movement in the direction of said flanges.
9. In a bleacher seat structure, a stringer, a member associated with the stringer and including a base and part rising therefrom to receive and be secured to a corner part of the stringer, a second member disposed beneath the base and upon which said base engages, flanges rising from said second member, one on each side the base and bolts extending between said flanges above said base and fore and aft the part rising therefrom for holding the base down upon said second member and against longitudinal movement in the direction of the flanges.
